[57] ABSTRACT

A motor cycle back rest which can be mounted by means of an articulate framework. The back rest proper can be adjusted up or down. Further adjustment of the backrest, consisting of angle of tilt, and movement toward and away from the front of the motor cycle, is provided by the design of the framework by which it is supported.

MOTOR CYCLE BACK RESTS

This invention relates to back rests for motor cycles, and more particularly to the type of back rest adapted to the necessary adjustments whereby it can be installed on any one of a wide range of motor cycles of different makes and models.

It is well known that back rests of various designs have been proposed in the past, however, unless such a device is designed to provide freedom of adjustment in any direction within a longitudinal plane of the cycle to which it may be attached, it does not serve its purpose in an entirely satisfactory manner. In addition to the fact that different makes of machines require different adjustments of auxiliary equipment installed thereon, the requirements of individuals using identical machines may also vary to a considerable extent.

It is the principal object of the present invention to provide a back rest which can be adjusted up or down, backward or forward, and which can be also sloped or tilted as required.

Another object of the invention is to provide all of the foregoing adjustments without conflicting limitations in the making of each.

A further object of the invention is the provision of a back rest which can be removed from a motor cycle while still retaining all of the adjustments except the actual point of fastening, or which can be collapsed as occasion demands.

These and other objects of the invention will become apparent during the course of the following description, taken in connection with the accompanying drawings forming a part hereof and in which:

FIG. 1 is a side elevation of the back rest.

FIG. 2 is a rear elevation.

FIG. 3 is a fragmentary top plan as seen from line 3—3 of FIG. 1.

FIG. 4 is a fragmentary bottom plan as seen from line 4—4 of FIG. 1.

Referring to the drawing in detail, the back rest proper comprises a base plate 10 with upper and lower frame support brackets 11 and 12 respectively. Slidably mounted upon the base plate is the actual rest 13 which will, of course, be provided with a cushion C as indicated in phantom on FIG. 1. The upper and lower ends of the back rest 13 are provided with a plurality of threaded apertures 14 spaced along the longitudinal median line thereof. Complimentary apertures are located in the brackets 11 and 12, one in each bracket, and they also pass through the base plate 10. These two apertures are so spaced as to coincide, in their respective alignments, with the apertures 14 in the back rest 13. This arrangement, as can be clearly seen from FIG. 1, permits adjustment of the back rest 13 upon the base plate 10 in one or another of a number of different positions. Thumb screws 15 are provided to lock the back rest in the selected, adjusted position.

Actual attachment of the back rest to a motor cycle is made by a framework of pivotally connected and adjustable tubular members. One of such members, the main frame support 16, is of bifurcated construction. One leg of the support extends rearwardly, in a substantially horizontal direction, from each side of a motor cycle to which it may be secured. Clips 17, or other suitable means, are provided for this purpose. The furcations of the support then follow an upward direction

and are integral with a transverse, horizontal connecting portion 18 of said support, as is illustrated in FIG. 2. It has been established that, in the majority of applications, the angular relationship between the rearwardly extending portion of the support 16 and the upwardly extending portion thereof is substantially uniform, however, adjustment of this relationship has been provided by means of conventional, radially serrated joints 19, located closely adjacent the lower bends of the support 16 in case such an adjustment is required.

A pair of upper side struts 20 are pivotally attached, at their remote ends, to lugs 21 on the bracket 11, at one end, and to a point intermediate the joints 19 and the upper end 18 of the main frame support 16. Connection between the back rest assembly and the main frame support is thereby made. Also pivotally attached to the upper bracket 11, by means of additional lugs 22, is a center strut 23. This strut passes under, and is adapted to be in contiguous relationship with the traverse portion 18 of the main frame support 16. An inverted U shaped clamp 24 straddles the transverse portion 18 of the main frame support 16 and is provided with apertures through which the center strut passes. Thumb screws 25, in the clamp 24, provides one of the points of adjustment of the aforementioned framework. In order to obviate the possibility of slippage at this point, a spring pin or cotter is inserted into the appropriate one of a number of apertures 27 in the center strut 23. Fastening of the clamp 24 establishes the longitudinal position of the upper end of the back rest with reference to the main support 16.

The angle of tilt of the back rest, and the prevention of further pivoting of the framework at the point of connection with the bracket 11 is maintained by the provision of a pair of lower struts 18. These struts are pivotally connected to the bracket 12 by means of pins or bolts extending through the members, and through lugs 29, in similar fashion to the connection of the framework at the upper end of the backrest. The lower struts are then swung upwardly between the upper struts 20, each pair being so spaced that contact is maintained between each adjacent member when in any adjusted position. Such positions are maintained by one of a pair of bolts or pins 30 passing through a single aperture in each of the upper struts 20, and engaging one of a series of spaced holes 31 through the lower struts 28.

It will be apparent from the foregoing description that a wide range of adjustments is made possible by the design so disclosed. Manipulation of the pins 30, and the clamp 24, will enable the back rest to be set at any desired angle, and at the right location relative to the seat S of the motor cycle to which it may be attached. Further adjustment of the back rest on the base plate can then be made as desired.

The terms "forward", "rearwardly" and "longitudinally" are used in the context having reference to an assembled unit mounted on a motor cycle.

Having illustrated and described a preferred embodiment of my invention, it should be understood that modifications may be made within the spirit and scope of the appended claims.

I claim:

1. A motor cycle back rest comprising a main frame support adapted to connection with a motor cycle, a

back rest located forward of and in substantially longitudinal alignment therewith, a rearwardly extending strut pivotally connected to the upper end of said back rest, and being further connected to said main frame member, the point of connection being longitudinally adjustable therewith, means adapted to maintain the angular relationship of an adjusted position of said main frame support and said strut, and further means adapted to maintain the spacial and angular juxtaposition of an adjusted relationship of said main frame support and said back rest.

2. A combination as in claim 1 wherein said back rest is adapted for elevatory adjustment.

3. A combination as in claim 1 wherein said connection between said strut and said main frame member comprises a clamp adapted to engage both of said elements.

4. A combination as in claim 1 wherein said first mentioned means comprises a pair of struts having one end pivotally attached to the upper end of said back rest, and having the other end pivotally attached to said main frame member.

5. A combination as in claim 1 wherein said second mentioned means comprises a pair of struts having one end pivotally attached to the lower end of said back rest, and having the upper end adjustably connected to said first mentioned means.

6. A combination as in claim 5 wherein said first mentioned means comprises a pair of struts having one end pivotally attached to the upper end of said back rest, and having the other end pivotally attached to said main frame member.
